UNITED STATES PATENT OFFICE.

CHARLES S. NEWSOM, OF ATHENS, OHIO.

DESIGN FOR A BROODER.

SPECIFICATION forming part of Design No. 32,508, dated April 10, 1900.

Application filed December 1, 1899. Serial No. 738,929. Term of patent 7 years.

To all whom it may concern:

Be it known that I, CHARLES S. NEWSOM, a citizen of the United States, residing at Athens, in the county of Athens and State of Ohio, have invented and produced a new and original Design for Brooders; and I do hereby declare the following to be a full, clear, and exact description of the same, reference being had to the accompanying drawing, forming a part thereof.

The design of my brooder comprehends, essentially, a circular base 1, supported upon legs 2, a circular wall 3 of less diameter than the base and rising therefrom, an open-work wall 4, partially surrounding the wall 3 at the periphery of the base, and a conical top or cover 5, closing the top of the wall 3, which latter is provided with suitable windows 6. The walls 3 and 4 define an open-air runway closed at one end by an end wall 7, having a doorway 8 and door 9, and at the opposite end by a lamp-box 10, extended above and

below the base and provided with a door 11. Between the lamp-box and end wall the wall 3 is cut away from the base to the cover or roof to form a doorway 12, closed by a door 13. An incline 14 extends downwardly from the base opposite the doorway 12 to the ground, and the runway is subdivided by radial partitions 15, provided with openings 16.

The essential feature of the design is a circular brooder having a conical top and partially surrounded by a circular runway, the ends of the runway being closed by an end wall and lamp-box.

What I claim is—

The design for a brooder herein shown and described.

In testimony whereof I affix my signature in presence of two witnesses.

CHARLES S. NEWSOM.
